UNITED STATES PATENT OFFICE.

EDWIN C. MEEKER, OF NEWARK, NEW JERSEY, ASSIGNOR TO SAMUEL I. KNIGHT, OF NEW YORK, N. Y.

WRITING-TABLET.

SPECIFICATION forming part of Letters Patent No. 339,570, dated April 6, 1886.

Application filed November 21, 1885. Serial No. 183,476. (No model.)

To all whom it may concern:

Be it known that I, EDWIN C. MEEKER, a citizen of the United States, residing at Newark, county of Essex, and State of New Jersey, have invented certain new and useful Improvements in Writing-Tablets, fully described and represented in the following specification and the accompanying drawings, forming a part of the same.

10 This invention relates to what are known to the trade as "writing tablets" or "pads"—that is to say, a tablet or pad composed of a number of sheets of writing-paper which are secured together at one or more of their edges in such manner that the sheets can be successively detached as they are written upon until the whole tablet is used. This manner of putting up writing-paper has of late become very popular, and there is now a great demand for 15 all classes of writing-paper put up in this form. The cheaper grades of these tablets usually consist simply of a stiff backing, of pasteboard, upon which the sheets of paper composing the tablet are placed, and to which they are secured 20 by means of a binding-strip, which is gummed to the backing and along two of the edges of the pile of sheets, so as to hold them to the back and to each other. In putting up the finer grades of paper, however, in the form 25 tablets it is desirable that the sheets should be secured along only one of their edges, and it is also desirable that, in addition to the stiff backing, the tablet should be provided with a cover, which, when the tablet is not in use, will 30 protect the paper from becoming soiled or wrinkled. It is also desirable that such tablets should be provided with a permanent blotter, by which the freshly-written sheet can be blotted before it is detached from the tablet. It 35 is also important, in a commercial sense, that these tablets, and particularly those which are composed of the finest grades of paper, and which are more especially designed for ladies' use, should be made to present an attractive 40 and ornamental appearance, corresponding to the quality of the paper composing the tablet. As, however, any considerable ornamentation upon the cover of the tablet makes a corresponding increase in its cost, it has heretofore 45 been found impracticable, in most cases, to pro-

vide these tablets with any but the plainest and most inexpensive covers, as the extra cost of an ornamental cover made the tablet so expensive as to materially interfere with its sale. I have found, however, that by making the 55 covers of these tablets in such form and of such character that when the paper of the tablet is used they can be removed and used for purposes of decoration it becomes practicable to provide these tablets with covers of a very 60 elaborate and ornamental character without making them objectionably expensive, as in such case the purchaser will willingly pay the extra cost of the cover, because it can be utilized after the tablet is exhausted. 65

To that end the present invention consists in a writing tablet or pad the cover of which is of such a character that it not only adds greatly to the appearance of the tablet, but can be readily detached when the tablet is exhausted, and will then form a highly-ornamental article for the decoration of a room. 70

As a full understanding of the invention can be best imparted by a description and illustration of the tablet, such description will now 75 be given, reference being had to the accompanying drawings, which illustrate the tablet, Figure 1 of said drawings being a plan view of the tablet, and Fig. 2 a partial longitudinal section thereof. 80

Referring to said figures, it is to be understood that *a* is a sheet of ordinary pasteboard, forming the backing of the tablet, and *b* the pile of sheets of paper of which the tablet is composed. The sheets of paper *b* are secured 85 to the backing *a* and to each other by means of a binding-strip, *c*, which is composed of cloth or other flexible material. This binding-strip is secured to the end of the backing *a*, and is gummed across the end of the pile of 90 sheets *b*, as shown in Fig. 2, all in the usual manner. The binding-strip *c* is extended beyond the upper edge of the pile of sheets *b* and forms a hinge for the cover *D*.

The cover *D* is composed of a sheet of pasteboard or card-board, *d*, the outer or upper face of which is covered by a piece, *f*, of satin or other similar fabric, which is pasted to the sheet of pasteboard *d*. The sheet *d*, after the fabric *f* is pasted to it, is embossed, so as to 95 100

- produce any desired design—such, for example, as that shown in the drawings—which embossing, owing to the nature of the fabric *f*, produces a very striking and ornamental effect. In addition to this some suitable design or picture may be printed or painted upon the fabric *f*, as also shown. After being embossed, the cover is provided with a lining, *e*, consisting of a sheet of paper, which is pasted to the inside of the cover and acts to conceal the embossing upon that side, and between which and the cover the end of the binding-strip *c* is secured, so as to form a hinge for the cover. The lining *e* not only serves to conceal the embossing upon the back of the cover while the latter is attached to the tablet, but performs the more important function of forming a backing for the embossed card or picture which the cover forms when it is detached from the tablet.
- 15 In some cases the cover *D* may be provided with a knot or bow of ribbon, which will serve to make the cover still more ornamental, and this ribbon or the satin *f* of the cover may be provided with such words as "A Merry Christmas" or "Easter Greeting," or any similar words, thus making the cover an appropriate Christmas or Easter card. If desired, the cover may also be provided around its edge with a suitable fringe.
- 20 Between the cover *D* and the sheets *b* there is interposed a permanent blotter, *g*, which is attached to the cover by a flexible connection, so as to be turned down onto the freshly-written sheet upon the top of the tablet.

By constructing the cover in this manner, 35 not only is the appearance of the tablet greatly improved, which renders it much more salable, but the cover itself is made to form a very beautiful article, which, after the paper of the tablet is exhausted, can be removed by cutting 40 the binding-strip *c* along the edge of the cover, and either mounted upon an easel or hung upon the wall as an ornament. It will thus be seen that the cover *D* is made to serve two purposes—it protects the paper of the tablet until 45 the latter is exhausted, and then serves as an article of decoration.

By thus designing and constructing the cover *D*, so that it will serve a useful purpose after it has served the purpose of a cover for the 50 tablet, it becomes practicable to make it of a comparatively elaborate and costly nature, thus making the tablet itself correspondingly attractive and salable.

What I claim is—

55 The herein-described writing tablet or pad, consisting of the backing *a*, sheets of paper *b*, binding-strip *c*, and the hinged cover *D*, composed of the sheet *d*, covered with satin or similar fabric and embossed with a suitable 60 design, substantially as described.

In testimony whereof I have hereunto set my hand in the presence of two subscribing witnesses.

E. C. MEEKER.
